UNITED STATES PATENT OFFICE.

SAMUEL W. RUSHMORE, OF PLAINFIELD, NEW JERSEY.

ENGINE-STARTING MOTOR.

1,235,162.

Specification of Letters Patent. Patented July 31, 1917.

Application filed September 27, 1912. Serial No. 722,629.

To all whom it may concern:

Be it known that I, SAMUEL WILLIS RUSHMORE, a citizen of the United States, residing at Plainfield, in the county of Union and

5 State of New Jersey, have invented new and useful Improvements in Engine-Starting Motors, of which the following is a specification.

This invention is an improved engine 10 starter for internal combustion engines and is of that type in which an axially movable gear is brought into mesh with an engine fly-wheel to transmit power to the latter and to the engine for starting the engine, 15 and is automatically moved axially out of mesh when the engine takes up its cycle of operation.

The invention resides primarily in the 20 means for automatically effecting this engagement and disengagement and the main objects of my invention are to render such engagement and disengagement more reliable, positive and instantaneous and without the use of gear-shift levers, ratchet 25 clutches, etc., which, with the necessary interlocking connections, involves considerable complication and expense. My novel arrangement results in a considerable saving in weight, space required and electrical 30 energy.

As one important feature of the invention, the shiftable pinion is pulled endwise into mesh by electro-magnetic action resulting from the closing of the circuit of the electric motor employed to rotate said pinion.

35 By means of this arrangement, the faster driving of the armature when the engine takes up its cycle of operation results in an increase in the counter-electromotive force 40 and a decrease in the endwise magnetic pull which permits a spring or other means to return the pinion to its normal disengaged position. As a simple and effective means for accomplishing this, I preferably connect the 45 pinion directly to the armature shaft and permit the shaft and armature to slide endwise within the field of the electric motor.

As a further important feature, I employ 50 helical gears, the inclination of the gear teeth being such that the end thrust thereon tends to hold the axially movable gear in mesh when it is rotated to drive the engine and shifts or aids in shifting it out of mesh when it is rotated by the engine when the 55 latter takes up its cycle of operation.

In the accompanying drawings which

show a preferred and desirable embodiment of my invention the parts are designated by similar characters in both of the figures which illustrates my invention diagrammatically and of which Figure 1 shows the normal disengaged position of the parts when the motor is inactive and Fig. 2 shows the parts in the position of engagement to start the engine when the motor is energized.

In the figures A indicates an electric motor having series wound field poles 2 and 3. 4 is an armature having an elongated shaft 4' running in bearings 5 and 6. 7 is a helical gear or pinion on the end of the armature shaft and adapted to engage with the helical gear teeth 8 cut in the rim of the engine fly wheel 9. 10 is a coiled spring in a bearing bracket 11 attached to the bearing 6 and 75 adapted (as it is compressed between the bracket end and the end of the shaft) to force the armature endwise out of the field a sufficient distance to throw the pinion 7 out of engagement with the fly wheel gear 80 8. 12 is an elongated commutator having brushes 14, 15. 16 is a storage battery, 17 a circuit closing switch and 18 and 19 are connections arranged to place the battery in series with the brushes, armature and field 85 windings.

It will be seen that so long as the switch 17 is open the coil spring 10 will force the armature 4 endwise out of line with the field poles 2 and 3 so that the gears 7 and 8 90 will be out of engagement as shown in Fig. 1.

Upon closing the switch 17, as shown in Fig. 2, a heavy current will at first flow from the battery through the armature and field coils, thus powerfully magnetizing the 95 field poles and causing the latter to exert a powerful horizontal attraction or pull on the armature 4. While in the displaced position shown in Fig. 1 the field will not exert its maximum rotative effect upon the armature 100 which will thus at first be moved rapidly in an axial direction, but with less than maximum rotative effort owing to the then reduced area of the effective magnetic field. The rotation being in the same direction as 105 the angular direction of the helical gear teeth the gears will promptly come into mesh and the rotative effort of the motor acting upon the inclined surfaces of the gear teeth will augment the horizontal effort 110 which the field exerts upon the armature to draw it into its normal running position in

line with the field magnet poles and it will then exert its maximum torque to start the engine. Of course the spring will always exert a pressure and the armature can never 5 reach exact alinement; at very least there will always be a slight displacement difficult to be shown in the drawing.

After the first few explosions in the engine cylinders the fly wheel will gain in 10 speed and drive the armature until the speed of the latter becomes so high that its counter electromotive force will so diminish the current passing through the motor that there will not be sufficient magnetic attraction 15 to hold the armature against the pressure of the spring 10 and the added outward thrust due to the angularity of the helical gear teeth when the motor is driven by the engine. As will be understood the 20 end thrust due to the angularity of the teeth is then reversed and the pinion under the influence of the spring and of the inclined teeth will be moved horizontally out of engagement with the fly wheel gear after 25 which the operator opens the switch 17 and the motor comes to rest in position shown in Fig. 1. This helical form of teeth is in some cases desirable but is not essential to the successful operation of the invention.

30 It will thus be seen that I have avoided the use of all gear shifting mechanism and that by the simple closing of the switch the armature is automatically thrown into engagement with the gear on the engine wheel 35 and after coming into full engagement the maximum effort will be imparted to the wheel to cause it to revolve. The particular arrangement is desirable for the reason given but it will be understood that my device is subject to various modifications without departing from the spirit of the invention.

Having described my invention, I claim.

1. An engine starting electric motor comprising a field magnet and an armature axially movable with respect to the field and normally displaced but adapted to be brought into driving relation with a device to be started thereby, an automatic means 45 for restoring the movable armature to its normal displaced position, said means being dependent upon the increased counterelectromotive force developed when the speed is increased through starting of the device.
2. An apparatus of the class described comprising in combination, an engine starting electric motor comprising a field magnet and an armature axially movable with respect to said field and adapted to be 50 brought into driving relation with a device to be started thereby, together with means for restoring the armature to its normal displaced position when the motor has reached a predetermined speed.
3. In an apparatus of the class described 55

and in combination, an electric starting motor comprising a field having a winding in series with the armature, an armature axially movable in said field and provided with a power-transmitting connection 70 adapted to engage a device to be started thereby, means normally tending axially to displace said armature shaft to disengage said connection in opposition to the attraction of said magnetic field when energized, 75 said displacing means being of such strength relatively to the field as to be overcome by the attraction of the field on the armature when excited by the normal working current and to overcome the attraction of the field upon the armature when the current is reduced by action of the increased counterelectromotive force due to increased speed 80 of the motor when the starting of the device is effected.

4. An electric starting motor comprising a field magnet and an armature arranged to have considerable axial movement within the field, in combination with means for engaging the motor with the device to be started through the agency of the axial movement of the armature and to be actuated by the motor current, and being so arranged that after the device has reached a predetermined speed the resultant decrease 90 in the current passing through the motor will cause the automatic disengagement of the motor from the device.

5. An electric starting motor comprising a field magnet and an armature arranged to have considerable axial movement within the field, in combination with helical gears for engaging the motor with the device to be started through the agency of the axial movement of the armature and to be actuated by the motor current, and being so arranged that after the device has reached a predetermined speed the resultant decrease 100 in the current passing through the motor will cause the automatic disengagement of the motor from the device.

6. In starting gearing for automobiles the combination of helical gear adapted to mesh with each other and transmit motion from a starting motor to the automobile engine, one of said gears being shiftable axially out of operative position by the end thrust caused by the helical form of the gear teeth when the engine is working, and means for shifting the axially movable gear into operative position at will.

7. In starting gearing for automobiles the combination of helical gears adapted to mesh with each other and transmit motion from a starting motor to the automobile engine, one of said gears being shiftable axially into and out of operative position and the gear teeth being inclined so that the axial thrust thereon will tend to hold the shiftable gear in operative position when it 110

- is rotated by the starting motor and will shift it into inoperative position when it is said circuit connections, the return axial movement of said second gear being effected by shifting the movable gear into operative position, both by the restriction of the magnetic pull, ⁵ at will, of said steamship being due to increased counter-electromotive force 70
- 10 In starting gearing for automobiles when the starting of the engine has been effected combination of helical gears adapted to mesh with each other and transmit motion of helical gears from a starting motor to the automobile 75
- 15 In apparatus of the class described, one of said gears being axially relative to the other into and out of engagement with the combination of an internal combustion engine, a helical gear connected thereto, a second helical gear adapted to mesh therewith the inclination of the gear teeth being such that the end with but normally offset in an axial direction thereon tends to hold the axially movable gear when it is rotated by the starting 80
- 20 motor in engagement with the other gear and will shift it out of engagement therewith when it is rotated by the engine, and means for shifting said axially movable gear into engagement with the other gear at will. 85
- 25 9. In an apparatus of the class described, in combination, an internal combustion engine, an electric motor, a helical gear operatively connected to said engine, a second helical gear adapted to mesh with said first gear and normally disposed offset in an axial direction from its meshing position, and means for moving said second gear endwise 90
- 30 into mesh with said first gear, said means comprising an endwise movable member coaxial with said motor and secured to said second gear, said member being moved endwise solely by solenoid action when said 95
- 35 motor is energized, said gears being automatically disengaged as the motor ceases to drive the engine when the starting of the engine has been effected. 100
- 40 10. In apparatus of the class described, the combination of an internal combustion engine, an electric motor, a helical gear operatively connected to said engine, a second helical gear adapted to mesh with said first gear and normally disposed offset in an axial 105
- 45 direction from its meshing position, and means for moving said second gear into mesh by solenoid action upon the closing of the motor circuit and the starting of the motor, the pitch of the gear teeth being such 110
- 50 that the axial thrust thereon will tend to hold the shiftable gear in operative position when it is rotated by the starting motor and will shift it into inoperative position when it is rotated by the engine. 115
- 55 11. In an apparatus of the class described, the combination of an internal combustion engine, an electric motor, a source of power, circuit connections whereby said motor may be energized from said source of power, a 120
- 60 helical gear connected to said engine, a helical gear connected to said motor and normally offset in an axial direction from meshing position, means adapted to automatically move said second gear axially into driving engagement with said first gear by 125
- 65 being adapted to automatically disengage the gears as the motor ceases to drive the engine, due to the increased counter-electromotive force of the motor when the starting of the engine has been effected. 130
